UNITED STATES PATENT OFFICE.

JOHN C. BLEVNEY, OF NEWARK, NEW JERSEY.

POLISHING-MACHINE.

1,052,455.

Specification of Letters Patent.

Patented Feb. 11, 1913.

Application filed February 15, 1912. Serial No. 677,774.

To all whom it may concern:

Be it known that I, JOHN C. BLEVNEY, a citizen of the United States, residing at Newark, in the county of Essex and State of New Jersey, have invented certain new and useful Improvements in Polishing - Machines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention has reference, generally, to improvements in polishing machinery, and the present invention has for its principal object to provide a compact, efficient and automatic polishing machine adapted, more particularly, to impart a high bright polish to objects having substantially round or cylindrical surfaces, and to thereby provide such objects with a smooth, uniform and highly finished surface, free from 25 blemishes, burns, or buckles, or blistered appearance.

The various specific objects of the present invention not at this time more particularly enumerated will be clearly understood from 30 the following detailed description of this invention.

With the various objects of the present invention in view, the said invention consists, primarily, in the novel automatic polishing 35 machine hereinafter set forth; and, the invention consists, furthermore, in the novel arrangements and combinations of the several devices and parts, as well as in the details of the construction of the same, all of 40 which will be more fully described in detail in the following specification, and then finally embodied in the clauses of the claim which are appended to and which form an essential part of the said specification.

45 The invention is clearly illustrated in the accompanying drawings, in which:

Figure 1 is a front elevation of a polishing machine showing one embodiment of the principles of the present invention; Fig. 2 50 is a transverse cross-section of the same, taken on line 2-2 in said Fig. 1, looking in the direction of the arrow *a*; Fig. 3 is a detail vertical longitudinal section, drawn on an enlarged scale, and taken on line 3-3 55 in said Fig. 2, looking in the direction of the arrow *b*; Fig. 4 is another detail vertical longitudinal section, also drawn on an

enlarged scale, and taken on line 4-4 in said Fig. 2, looking in the direction of the arrow *c*; Fig. 5 is a detail transverse section illustrating the reversing mechanism of the traveling carriage supporting the polishing or buffing wheels; Fig. 5^a is a detail longitudinal section of means for operating the said reversing mechanism of said traveling carriage; Fig. 6 is a detail transverse cross-section, drawn on an enlarged scale; and taken on line 6-6 in Fig. 1, looking in the direction of the arrow *d*, said view illustrates the driving mechanism for rotating the objects to be polished; Figs. 7 and 8 are respective vertical longitudinal sections, drawn on an enlarged scale, of the chuck spindles for supporting the objects to be polished; Fig. 9 is a vertical longitudinal section of the driving mechanism located at the left end of the machine, and Fig. 10 is a similar view of the driving mechanism located at the right end of the machine, both of said views being drawn on an enlarged scale; Fig. 11 is a vertical section of means for adjusting and controlling the work-carrying mechanism with relation to said polishing or buffing wheels, the same being drawn on an enlarged scale, and taken on line 11-11 in said Fig. 1; Fig. 12 is a horizontal cross-section of said means for adjusting and controlling the work carrying mechanism with relation to said polishing or buffing wheels, the same being drawn on an enlarged scale, and taken on line 12-12 in said Fig. 11; Fig. 13 is another vertical section of the same, taken on line 13-13 in said Fig. 1; and Fig. 14 is a detail view illustrating a latch mechanism connected with said means for adjusting and controlling said work carrying mechanism.

Similar characters of reference are employed in all of the said above described views, to indicate corresponding parts.

Referring now to the said drawings, the reference-characters 1 and 1' indicate the respective end frames or standards of the machine, the same being joined together in proper relation to each other by a plurality of suitably disposed longitudinally extending struts or girders 2. The end frames or standards 1 and 1' are provided with bearing-portions in the form of bearing ribs 3 and 3' respectively. Journaled upon said bearing-ribs are journal-blocks 4 and 4', each of which is provided with an annular groove 5 and 5' adapted to engage, respectively, said bearing ribs 3 and 3'.

The said journal blocks are respectively provided with flanges 6 and 6', to which are secured the respective end-plates 7 and 7' of a revoluble frame member. Said revoluble frame-member comprises said end-plates 7 and 7' and the interconnecting longitudinally extending rods or struts 8. Connected with each of said rods or struts 8 of said revoluble frame-member are pairs of oppositely extending screw-threaded arms 9. Supported in connection with said screw-threaded arms 9 are the means for adjusting and controlling the work carrying mechanisms. Said work carrying mechanisms and their respective adjusting and controlling means each comprises a longitudinally extending supporting plate 10 provided, preferably, with flanged marginal edges 11. Connected with each supporting plate 10 are a pair of rearwardly extending supporting arms 12, each provided with suitably disposed teeth providing a rack 13. The said supporting arms 12 are each slidably supported in a guide-portion 14 formed in casings 15 which are movably related to the said screw-threaded arms 9, in such a manner that each of said supporting plates 10 is arranged so as to extend longitudinally. Journaled in bearings 16 formed upon said casings 15 are the respective ends of a longitudinally extending shaft 17, provided with pinions 18 which mesh operatively with the racks 13 of said supporting arms 12, such arrangement insuring the uniform and simultaneous movement of said supporting arms 12 in carrying forward or withdrawing said supporting plate 10. Connected with the end of each guide-portion 14 of said casings 15 is a latch-mechanism which serves to lock said supporting arms 12, and said supporting plate 10 connected therewith, in their forwardly moved position. Said latch-mechanism comprises a yoke-piece 19, arranged to move laterally of said guide-portion 14, and provided upon one side with a stop-pin 20 which slides in an opening 21 in said guide-portion 14, so as to engage in holding relation therewith a groove or notch 22 formed in said supporting-arm 12 adjacent to its inner end. Arranged between the opposite side of said yoke-piece and said guide-portion, and seated upon retaining-pins 23 fixed upon said respective parts, is a spring-member 24 for actuating said latch-mechanism to cause the proper engagement of said stop-pin 20 with said groove or notch 22. The means providing for the vertical adjustment of said supporting plates 10 comprises internally screw-threaded nut-pieces 25, which engage or ride upon the respective screw-threaded arms 9. Said nut-pieces 25 each ride within one of said casings 15, so as to cause the upward or downward movement of the latter, whereby said supporting arms 12, and the respective supporting plates 10 connected therewith are carried up or down in accordance with the desired vertical adjustment. In order to assure the uniform and simultaneous movement of the respective casings 15 from which extend, in the manner above described, the respective supporting arms 12 carrying the supporting plate 10, there is provided a longitudinally extending shaft 26, the opposite ends of which are connected with worm-members 27 journaled in bearing portions 28 of the respective longitudinally opposite casings 15. Each nut-piece 25 is provided upon its circumferential surface with worm gear teeth 29 which mesh with the respective worm-members 27. Each longitudinal shaft 26 thus arranged is provided with a suitably located hand-wheel 30, which serves to turn said shaft 26, thereby operating said worm-members 27 to simultaneously turn said nut-pieces 25 of longitudinally opposite casings 15, and whereby the latter are moved upwardly or downwardly upon said screw-threaded arms 9 to which they are connected, thus causing said uniform upward or downward vertical adjustment of the said supporting plate 10 connected therewith.

Each of said supporting-plates 10 is adapted to carry a means for holding and rotating the work to be polished, such for example as tubes 31. This mechanism comprises an adjustable spindle device and a driving or rotating spindle device. The said driving or rotating spindle device comprises a bearing-member 32 supported upon a base-plate 33 adapted to be received upon said supporting-plate 10, between the marginal flanges thereof, and permanently secured by means of screws, or other fastening means, preferably to the left hand end of each supporting-plate 10. Journaled so as to rotate in said bearing-member 32 is a spindle 34, provided with a collar 35 preventing any backward longitudinal movement thereof. Secured upon the free end of said spindle 34 is a chuck-member 36 adapted to securely engage said tubes 31, so as to impart the rotation of said spindle 34 thereto. Of course, it will be understood that said chuck-members 36 may be made in any desirable form or style, as may seem best adapted to the work to be handled, and said chuck-member 36 may be connected with said spindle 34, so that its rotation may be stopped independently of the spindle 34 if desired. The said adjustable spindle device comprises a bearing member 37 supported upon a base-plate 38, adapted to be received upon said supporting-plate 10 between the marginal flanges thereof. Said bearing member 37 is retained in any desired adjusted position upon said supporting plate 10 by means of a clamp-piece 39, which en-

gages, in binding relation, both said base-plate 38 and said supporting-plate 10. Each clamp-piece is provided with a clamp-screw 40, for tightening or binding said clamp-piece in its holding position. By such means said adjustable spindle device may be shifted longitudinally upon said supporting-plate 10, and secured in such adjusted position as will accommodate the relation of the driving or rotating spindle device and the adjustable spindle device to the length of tube to be worked upon. Slidably supported in said bearing member 37 is a holding-member 41 adapted to hold a center-point or chuck 42, which engages the opposite end of said tube 31, said tube may be provided with an inserted disc or washer 43 to be engaged by said center-point or chuck. Said holding-member 41 is provided with a 10 reduced shank 44 which extends rearwardly and projects beyond the rear end of said bearing member. Said end of the projecting end of said shank 44 is provided with a collar 45 which, engaging the end of a bearing member, limits the forward movement of said shank and holding member, as actuated by a spring member 46 arranged to maintain engagement therewith. When it is desired to place in connection with, or remove, 15 said respective spindle devices a tube, or the same is caused to engage said center-point or chuck 42, and by pressing backwardly against the tension of said spring member 46, the opposite end of said end of shank 44 is registered with said clutch-member 47 of said rotating spindle device, so as to effect the engagement of the same. When the forward pressure is released, said spring member 46 moves said holding-member 41 rearwardly, so as to disengage the center-point or chuck, and move into its operative position.

The means for rotating the driving or rotating spindle devices consists of the following mechanism--Said journal block 4 is provided with a longitudinally extending opening 47 in which is journaled a sleeve 48. Secured upon the outer end of said sleeve 48 is a gear-wheel 49, which meshes with a pinion 50 rotatably mounted upon a stud-shaft 51, said stud-shaft being secured to and projecting from said end-frame or standard 1. Connected with said pinion 50 is a driving-pulley 52, which is driven by a belt 53 from the source of power, and which imparts its motion to said pinion 50 to drive said gear-wheel 49 and sleeve 48. Said sleeve 48 projects through said end-plate 7 of said revolute frame member, and secured to this inwardly projecting end of said sleeve 48 is a bevel-gear 54. Surrounding said bevel-gear 54, and secured to said end-plate 7, is a parted gear-casing 55, providing bearing portions 56, in which are journaled the journal members 57 of a plurality of radially disposed bevel

pinions 58, which mesh operatively with, and which are driven by, said bevel-gear 54. Connected with the outwardly projecting steams 59 of said bevel-pinions 58 are universal or knuckle-joints 60, whereby radiating transmission shafts 61 are operatively connected with the bevel pinions. Connected with each moving or rotating spindle 31 is a bevel-gear 62 which meshes with a bevel-gear 63 mounted upon and rotated by one of said transmission shafts 61. Each bevel-gear 63 is provided with an internal pin or key, (not shown) which engages a longitudinally extending groove 64 in said shaft 61, thereby permitting a longitudinal movement of said shaft 61 with relation to said bevel-gear 63 while thus assuring the driven connection of the latter with the former. Each of said revolving bevel gears 62 and 63 is radially enclosed in a gear-casing 65. It will be understood that the above described mechanism, in addition to providing the driving or rotating motion, will produce a longitudinal movement of the driving or rotating spindle 31, so as to maintain the same in the direction of the longitudinal axis of the revolving spindle 31, and to effect the adjustment of the position of said supporting spindle 31, so as to avoid any interference with the driving or rotating spindle 31, or the longitudinal axis of the latter.

Secured to the outer end of said sleeve 48, provided with a gear-wheel 49, is a spring 66 in which is journaled a stud-shaft 67. Secured to the outer end of said stud-shaft 67 is a bevel-gear 68 which meshes with a pinion 69 driving a sleeve 70, which is journaled at the source of power, and which is driven by a belt 71, passing over a pulley 72, so as to drive said bevel-gear 68. Said sleeve 70 is journaled on the outer end of said revolving spindle 31, so as to effect this inwardly projecting end of said spindle 31 a gear-member 73. Connected with said sleeve 70 is a feed-screw shaft 74, which is provided with a feed-screw 75, which is journaled in a bearing member 76, which may be located upon said sleeve 70 of said sleeve 67, or upon some other convenient part of said revolute frame. Secured upon said respective feed-screw shafts are gear-members 76 and 77, which respectively mesh with said gear-member 70 of said sleeve 67, and by means of which said respective feed-screw shafts are rotated. Said gear-members 76, 76 and 77 are suitably inclosed in a casing 78, if desired. Journaled in said respective sleeves 67 and 70 are the opposite cylindrical journal ends 79 and 79' of a central longitudinally ending square

driving shaft 80, said respective journal ends 79 and 79' project beyond the outer ends of said respective sleeves 48 and 67, and are provided with pulley-wheels 81 and 81', over which run the respective driving belts 82 and 82' by means of which said square driving shaft 80 is driven from the source of power. Mounted within said revolving frame is a polishing or buffing wheel carrier comprising, a main casting 83, preferably parted for easy assembling, to which is secured, at one end, radiating arms 84. The said radiating arms 84 are each provided with bifurcated bearing blocks 85, each bearing block 85 being adapted to support a pair of inclined traction-rollers 86, which ride upon one of the respective longitudinally extending rods or struts 8 of said revoluble frame, whereby said polishing or buffing wheel carrier is always maintained in a longitudinally movable relation to said revoluble frame. Said main casting 83 is provided with a central longitudinal opening 87, in which is journaled a rotatable sleeve 88, provided with a centrally disposed squared opening 89, through which extends said square driving-shaft 80, in such a manner, that while said sleeve 88 is free to slide longitudinally upon said square driving-shaft it nevertheless receives its rotary movement from the same. Arranged within said main casting 83, and secured upon said sleeve 88 so as to rotate therewith, is a spiral gear 90. Connected with said main casting 83 are a plurality of outwardly extending and angularly disposed bearing-arms 91, in which are journaled polishing or buffing wheel mandrels 92, upon the outer free ends of which are secured, between the stationary hub-plate 93 and the removable hub-plate 94, the polishing or buffing wheels 95. Secured upon each mandrel 92 is a spiral gear 96, inclosed in a suitable gear casing 97 formed upon said casting 83. Each of the said spiral-gears 96 meshes operatively with said spiral gear 90 secured upon said sleeve 88, thus the rotation of said square driving-shaft 80 is imparted to said polishing or buffing wheel mandrels, and the polishing or buffing wheels connected therewith, by said sleeve 88 and the intermeshing spiral gears 90 and 96. Formed in connection with said main casting 83, adjacent to the ends thereof, are outwardly projecting arms 98 and 98', each provided, in their free ends with openings 99 and 99' respectively, through which extend said respective right and left feed-screw shafts 73 and 74. Extending outwardly from said main casting 83 are other arms 100, arranged at right angles to said arms 98 and 98', the same being provided with openings 101 in which is slidably supported a carrying sleeve 102. Se-
65 cured upon said carrying-sleeve in a proper location, both with reference to their position on said sleeve and their relation to each other, are a right shifting cam 103 and a left shifting cam 103'. Extending through said sleeve 102 is a rod 104, the same extending longitudinally of said revoluble frame, and the ends being properly supported in bearing-members, such for example as the bearing member 105. Said rod 104 may be screw-threaded, as shown, to permit of any desired adjustment, as to location, of stop-members 106 and 106' carried thereby. The openings 107 at each end of the carrying sleeve 102 are enlarged for the reception of the respective coil springs 108, which are seated in engagement with the ends or bottom of said openings 107. Each end of said carrying sleeve 102 is provided in its outer surface with a notch or grooved portion 109, the same being adapted to be engaged at proper times by spring-actuated latch-pieces 110, which are pivotally connected with some suitable portion of said main casting 83. Each latch-piece 110 is provided with a forwardly extending cam end-portion 111, which projects beyond the ends of said carrying sleeve 102. The said casting 83 is further provided with other arms 112, extending outwardly therefrom and at right angles to said arms 98 and 98', and oppositely of said arms 100, the same supporting a rod 113 upon which is pivotally connected a yoke-frame 114. Said yoke-frame extends around said casting 83, and is provided upon the side opposite to its pivot with a pair of lugs or projections, 115 and 115' respectively, which straddle said carrying sleeve 102, and which lie in the path of said left and right shifting cams 103 and 103'.

frame in a wrong direction, or backward, there is provided in connection with the end-plate 7 a ratchet-wheel 117, which is normally engaged by the step-sleeve 102 of a gravity balanced lever 118, normally mounted in connection with said end-plate 7, and standard 1, said lever being provided with a weighted arm 120 for indicating the same. The said lever 118 is so arranged that it so disposes said step-sleeve 102 in relation to said ratchet-wheel 117 as to permit the latter to ride over the teeth, when the reversible frame is turned in a wrong direction, but arrests the same by being turned in an opposite direction.

frame 111. Said yoke-frame 114 is oscillated automatically to accomplish this result in the following manner:—During the forward stroke 116, as shown in contact with the receding end screw-sight 114 of the latter, the main carriage 112, including wheel 113, moves to the right, carrying the same toward the stop 106, which has been properly adjusted upon the road bed. As the end of said sleeve 102 approaches said stop 106, the coil spring 108 is caused to contact with said stop 106, thereby preventing the sleeve 102 from passing beyond the engagement of the ratchet-wheel 117 therewith. When a

Having thus described the invention, what is desired to be secured is a device, which, when compressed, the structure of the novel, resilient, and adjustable device, of which the member 110 is made according to the principles of the foregoing description, and therewithal effected present invention, it remains, however, to describe the manner of the latch member 110 forth the operation and manner of use of the novel device, in which, in the said sleeve 102, the member 110 is to be secured, as follows:

is carried around by the revolving frame to the hand of the operator again, the same is completely polished, and may be removed, and another tube inserted. When tubes of 5 different diameters are to be polished, the work holding devices may be easily raised or lowered to accommodate the tube to a proper contact with the polishing or buffing wheels, by turning the hand-wheel 30 to 10 adjust the means carrying said supporting plates 10, upon the screw-threaded arms 9, all in a manner clearly to be understood from an inspection of the drawings, and in the same manner adjustment may be obtained 15 to compensate for the wear of buffing or polishing wheels. It will also be clearly evident that by this means a very delicate adjustment of the pressure of the polishing wheels upon the work, may be also obtained, so that although the polishing of 20 the tubes is effected in an automatic manner, yet more perfect and uniform results can be obtained in the finished surface than can be obtained even by hand polishing, 25 since all danger of uneven pressure is obviated, and burns, blisters and blemishes avoided.

As many changes may be made in the above described construction of my invention and its detail parts, and many apparently widely different embodiments of my invention could be made without departing from the scope thereof, I intend that all matter contained in the above description 30 or shown in the accompanying drawings shall be interpreted as illustrative and not in a limiting sense. I desire it also to be understood that the language used in the following claims is intended to cover all 35 generic and specific features of the invention herein described, and all statements of the scope of the invention, which, as a matter of language, might be said to fall therebetween. Hence, I do not limit my present 40 invention to the exact arrangements and combinations of the devices and parts as described in the said specification, nor do I confine myself to the exact details of the construction of the said parts, as illustrated 45 in the accompanying drawings.

I claim:

1. In a device of the class described, a revoluble frame-member, work holding means carried by said frame-member, a polishing element within said revoluble frame-member, and means for reciprocating said polishing element longitudinally.

2. In a device of the class described, a revoluble frame-member, work holding 50 means, means for adjustably supporting said work holding means in connection with said revoluble frame-member, a polishing element mounted within said revoluble frame-member, and means for reciprocating said polishing element longitudinally.

3. In a device of the class described, a revoluble frame-member, work holding devices carried by said frame-member, means connected with said work holding devices for rotating the work, a polishing element within said revoluble frame-member, and means for reciprocating said polishing element longitudinally. 70

4. In a device of the class described, a revoluble frame-member, work holding devices, means for adjustably supporting said work holding devices in connection with said revoluble frame-member, means connected with said work holding devices for rotating the work, a polishing element within said revoluble frame-member, and means for reciprocating said polishing element longitudinally. 75

5. In a device of the class described, a revoluble frame-work, screw-threaded arms connected with said frame-work, longitudinal supporting-plates, means connected with said screw-threaded arms for adjustably carrying said supporting-plates, a rotatable work holding spindle device and an adjustable work holding spindle device connected with said supporting-plates, a power transmission mechanism for rotating said rotatable work holding spindle devices, a polishing element, and means for reciprocating said polishing element longitudinally. 80

6. In a device of the class described, a revoluble frame-work, screw-threaded arms connected with said frame-work, longitudinal supporting-plates, means connected with said screw-threaded arms for adjustably carrying said supporting-plates, a rotatable work holding spindle device and an adjustable work holding spindle device connected with said supporting-plates, a power-transmission mechanism for rotating said rotatable work-holding spindle devices, a longitudinally and centrally disposed driving shaft, a polishing wheel carrier, a plurality of polishing wheels, means connected with said polishing wheel carrier and operated by said driving-shaft for rotating said polishing wheels, and means for reciprocating said polishing wheel carrier longitudinally. 105

7. In a device of the class described, a revoluble frame member, work-holding means carried by said frame-member, a longitudinally and centrally disposed driving-shaft, a polishing wheel carrier, a plurality of polishing-wheels, means connected with said polishing wheel carrier and operated by said driving shaft for rotating said polishing wheels, and means for reciprocating said polishing wheel carrier longitudinally. 110

8. In a device of the class described, a pair of side-frames, a revoluble frame-member, comprising end-plates provided with inter-connecting longitudinal arms, journal-blocks provided with longitudinal openings connected with said end-plates and 130

1. In a device of the class described, a pair of side frames, a longitudinal driving-shaft, a pair of longitudinal struts, longitudinal supporting-bars, means connected with said longitudinal struts for adjustably carrying said supporting-plates, a rotatable work holding-spindle device and an adjustable work holding-spindle device connected with said supporting-plates, a sleeve rotatably mounted in the opening of one of said journal-bearings, a power transmission mechanism for driving said sleeve, a bevel-gear mounted on said sleeve, a plurality of bevel-pinion gears, said sleeve supporting said bevel plates, each in mesh with said bevel-gear, means for driving each of said transmission shafts being connected with each of said bevel-pins, a pair of longitudinal frame-members connected with said longitudinal struts, a longitudinal driving-shaft, a longitudinal spindle adapted to be operated by said respective transmission shafts, a longitudinal frame-member, and means for reciprocating said polishing-element longitudinally.
2. In a device of the class described, a pair of side frames, a longitudinal driving-shaft, a longitudinal frame-member, comprising a longitudinal frame-member, a pair of longitudinal-blocks provided with longitudinal openings connected with said longitudinal frame-member, and journaled in said side frames, a pair of longitudinal arms mounted in said longitudinal struts, longitudinal supporting-plates connected with said supporting-plates, means for adjustably carrying said supporting-plates, a rotatable work holding-spindle device and an adjustable work holding-spindle device connected with said supporting-plates, a sleeve rotatably mounted in the opening of one of said journal-bearings, a power transmission mechanism for driving said sleeve, a bevel gear mounted on said sleeve, a plurality of bevel-pins, means for supporting said bevel-pins in mesh with said bevel-gear, transmission shafts, each transmission shaft being connected with one of said bevel-pins, a gear mechanism connected with each adjustable work holding-spindle adapted to be operated by said respective transmission shafts, a longitudinally and centrally disposed driving-shaft, a polishing-wheel carrier, a plurality of polishing-wheels, means connected with said polishing-wheel carrier and operated by said driving-shaft for rotating said polishing-wheels, and means for reciprocating said polishing-wheel carrier longitudinally.
3. In a device of the class described, a revoluble frame-member, work holding devices, means for adjustably supporting said work holding devices in connection with said revoluble frame-member, means connected with said work holding devices for rotating the work, a longitudinally and centrally disposed driving-shaft, a longitudinal sleeve journaled in said longitudinal driving-shaft but adapted to be rotated thereby, a spiral gear connected with said sleeve, angularly disposed bearing arms connected with said main casting, mandrels rotatably mounted in said bearing-arms, spiral gears connected with said mandrels and meshing with said spiral gear on said sleeve, polishing-wheels connected with the free ends of said mandrels, and means for reciprocating said polishing-wheel carrier longitudinally.
4. In a device of the class described, a longitudinally disposed frame-member, work holding devices means for adjustably supporting said work holding devices in connection with said longitudinal frame-member, means connected with said work holding devices for rotating the work, a longitudinally and centrally disposed driving-shaft, a longitudinal sleeve journaled in said main casting, said sleeve being free to move longitudinally upon said driving-shaft but adapted to be rotated thereby, a spiral gear mounted on said sleeve, angularly disposed bearing arms connected with said main casting, mandrels rotatably mounted in said bearing-arms, spiral gears connected with said mandrels and meshing with said spiral gear on said sleeve, polishing-wheels connected with the free ends of said mandrels, and means for reciprocating said polishing-wheel carrier longitudinally, comprising a pair of oppositely threaded feed-screw-shafts, means for rotating said feed-screw-shafts, a yoke-frame pivotally connected with said main-casting, threaded shoes connected with said yoke-frame, and means for automatically oscillating said yoke-frame to cause the alternate engagement of said threaded shoes with said respective feed-screw-shafts.
5. In a device of the class described, a polishing-wheel carrier, a plurality of polishing-wheels, means for rotating said polishing-wheels, means for automatically reciprocating said polishing-wheel carrier, longitudinally, and means for presenting the work to be polished in contact with said rotating and longitudinally reciprocated polishing-wheels at an acute angle to the direction of rotation of the said polishing-wheels.
6. In a device of the class described, a longitudinal driving-shaft, a pair of feed-screw-shafts, a polishing-wheel carrier slidably related to said driving-shaft and said feed-screw-shafts, a plurality of polishing-wheels, means operated by said driving-shaft for rotating said polishing-wheels, automatically operated means connected with said polishing-wheel carrier for alternately engaging said feed-screw-shafts to cause a longitudinal reciprocable sliding

- movement of said polishing-wheel carrier, and means for presenting the work to be polished in contact with said rotating and reciprocated polishing-wheels:
- 5 14. In a device of the class described, a longitudinal driving shaft, a pair of feed-screw shafts, a polishing wheel carrier slidably related to said driving shaft and said feed-screw shafts, a plurality of polishing 10 wheels, means operated by said driving shaft for rotating said polishing wheels, a longitudinally extending rod, stop-members adjustably mounted on said rod, a carrying sleeve slidably related to said polishing-wheel carrier, left and right shifting cams carried by said carrying sleeve, a yoke-frame pivotally connected with said polishing-wheel carrier, projections on said yoke-frame adapted to be engaged by said shifting 15 cams, threaded shoes connected with said yoke-frame for alternately engaging said respective feed-screw shafts, coil-springs engaging each end of said carrying sleeve and adapted to be compressed by engagement with said stop-members, latch-mechanisms engaging each end of said carrying sleeve to retain the same against movement during the compression of said coil-springs but adapted to be released by 20 engagement with said stop-members when said coil-springs are compressed, and means for presenting the work to be polished in contact with said rotating and reciprocated polishing-wheels.
- 25 15. In a device of the class described, the combination with a revoluble frame-work of a polishing wheel carrier, a plurality of polishing wheels, means for rotating said polishing wheels, means for automatically reciprocating said polishing wheel carrier longitudinally within said frame-work, and adjustable means carried by said frame-work for presenting the work to be polished in contact with said rotating and longitudinally reciprocated polishing wheels.
- 30 16. In a device of the class described, a work supporting means comprising screw-threaded arms, a nut-piece on each arm, a casing surrounding each nut-piece, guide-portions connected with each casing, supporting arms slidably mounted in said guide-portions, a supporting plate connected with a pair of said supporting arms so as to longitudinally straddle a pair of said screw-threaded arms, means for interconnecting the supporting arms of said supporting plate to insure the simultaneous movement of the same, means for operating the nut-pieces of each screw-threaded arm 35 to simultaneously raise or lower said casings upon said screw-threaded arms, and means carried by said supporting plate for holding the work to be polished.
- 40 17. In a device of the class described, a work supporting means comprising screw-threaded arms, a nut-piece on each arm provided with external worm-gear-teeth, a casing surrounding each nut-piece, guide-portions connected with each casing, supporting arms slidably mounted in said guide-portions, a supporting-plate connected with a pair of said supporting arms so as to longitudinally straddle a pair of said screw-threaded arms, spring-actuated latch-members adapted to engage said supporting arms to retain the same in their forwardly moved positions, means for interconnecting the supporting-arms of said supporting-plate to insure simultaneous movement of the same comprising, a rack connected with each supporting-arm, a pinion engaging each rack, and a longitudinal connecting shaft upon which said pinions are mounted, means for operating said nut-pieces of each screw-threaded arm to simultaneously raise or lower said casings upon said screw-threaded arms comprising a worm-member journaled in each casing and engaging the worm gear-teeth of said nut-pieces, a longitudinal connecting shaft connecting said worm-members, and a hand-wheel on said shaft, and means carried by said supporting plate for holding the work to be polished.
- 45 18. In a device of the class described, a polishing element, a rotary polishing wheel, and a plurality of adjustable work holding means adapted to present the work in contact with different points of the polishing wheel surface.
- 50 19. In a device of the class described, a polishing element, a plurality of rotary polishing wheels connected therewith, and a plurality of adjustable work holding means adapted to present the work in contact with different points of each polishing wheel surface.
- 55 20. In a device of the class described, a polishing element, a driving shaft, a plurality of rotary polishing wheels connected with said polishing element, said polishing wheels being mounted in planes angularly disposed with relation to the axis of said driving shaft, intermediate transmission mechanism between said driving shaft and said polishing wheels, and work-holding means adapted to present the work in contact with said polishing wheels.
- 60 In testimony, that I claim the invention set forth above I have hereunto set my hand this 13th day of February, 1912.
- JOHN C. BLEVNEY.
